UNITED STATES PATENT OFFICE.

FERDINAND J. HAGEN, OF NEW YORK, N. Y.

CIGAR-BUNCHING MACHINE.

SPECIFICATION forming part of Letters Patent No. 415,943, dated November 26, 1889.

Application filed October 12, 1888. Serial No. 287,920. (No model.)

To all whom it may concern:

Be it known that I, FERDINAND J. HAGEN, of the city, county, and State of New York, have invented certain new and useful Improvements in Cigar-Bunching Machines, of which the following is a specification.

This invention relates to a machine for making cigar-bunches in which fillers composed of large-sized scraps are used, so that the cutting of the scraps into smaller pieces of uniform size is dispensed with; and the invention consists of a cigar-bunching machine which comprises a supply-hopper having a laterally-extending contracted throat, an intermittently-actuated feed-roller located in said throat, a vertically-movable and horizontally-reciprocating feed-block that enters through an opening of the throat and feeds the tobacco toward the mouth of the throat, a vertically-reciprocating cutting-knife, and an oscillating mold at the mouth of the throat. The tobacco in the mold is transferred along an arc-shaped guide-plate to a horizontal rolling-table at the lower end of said guide-plate, and deposited in the pocket of the rolling-table by a plunger guided in the shell of the mold, and then rolled into the binder by the action of the rolling mechanism.

The working parts of my improved bunching-machine are operated by a series of cams on a driving-shaft and intermediate mechanism in such a manner that at each revolution of said shaft a complete bunch is formed.

In the accompanying drawings, Figure 1 represents a side elevation of my improved cigar-bunching machine. Fig. 2 is a vertical longitudinal section of the main parts of the same, taken on line $x-x$, Fig. 4; Fig. 3, a plan of the feed mechanism with the supply-hopper removed and parts drawn in section. Fig. 4 is a front elevation. Figs. 5, 6, and 7 are details of the mold, mold-box, and mold-carrier. Figs. 7^a and 7^b are details showing the different positions of the mold and mold-box relatively to the pocket of the rolling-table, and Figs. 8 to 14 are side views of the different cams employed for imparting motion to the working parts of the machine. Fig. 15 is a detail of the adjustable connection whereby the stroke of the feed-block is regulated.

Similar letters of reference indicate corresponding parts.

Referring to the drawings, A represents the supporting-frame of my improved cigar-bunching machine, which frame consists of two upright side standards and two horizontal brackets A' and A², of which the bracket A' is located at the front end of the machine and serves to support the rolling mechanism, while the bracket A² is located at the rear end of the machine and serves to support the supply-hopper B and the feed mechanism. A driving-shaft S is supported in bearings at the upper parts of the standards A, and provided with cams C' to C⁷, which are shown in detail in Figs. 8 to 14, said cams serving to impart by cam-grooves of proper shape the required motion to the different working parts of the machine.

A supply-hopper B is provided with a contracted horizontally-extending throat b, which is supported on the rear bracket A² and connected at its conically-enlarged rear end with the supply-hopper B, into which tobacco scraps of proper size are placed. In the enlarged rear end of the throat b is located an intermittently-rotating feed-roller b', which is provided with teeth or ribs and intermediate pockets or spaces between said ribs, which take up a certain quantity of tobacco and move it along the curved rear wall of the throat, so as to feed it forward into the contracted part of the throat b. Intermittent rotary motion is imparted to the feed-roller b' by a ratchet-wheel b², which is attached to the outer end of the shaft of the feed-roller b', the teeth of said ratchet-wheel extending in a direction opposite to the ribs of the feed-roller. The ratchet-wheel b² is engaged by a pawl b³, which is applied to the pivot-rod d⁶ of a feed-block D, as shown in Fig. 1. The pawl b³ drops by its own weight into the teeth of the ratchet-wheel b², and turns the feed-roller b' at each backward stroke of the feed-block D for one or more teeth, according to the quantity of tobacco to be fed into the throat b.

The feed-block D is guided in a top opening of the enlarged rear part of the throat b and serrated at its under side, so as to take hold of the tobacco and feed it forward into the contracted front end of the throat b. The feed-block D is supported at a slight inclination to the bottom of the throat b and receives

vertically-reciprocating and horizontally-reciprocating motions by suitable levers from the cams on the shaft S—that is to say, the feed-block is first lowered and moved forward 5 in the top opening of the feed-box and then raised and moved backwardly in the same. A flat spring D' is attached to the lower front end of the feed-block D and extended along the under side of the top plate of the throat 10 b to a sufficient distance in the same, so that no parts of the tobacco fed forward by the feed-roller b' and block D can pass into the opening between the feed-block and the top plate of the throat b, nor crowd up or get 15 choked in the same. The flat spring D' is equal in width with the feed-block and throat, and remains in contact with the under side of the top plate of the throat whatever be the position of the feed-block. Vertically-recip- 20 roating motion is imparted to the feed-block D by an elbow-lever d', which is fulcrumed to the supporting-frame A, and engaged at its upper end by the cam-groove of the cam C', (shown in Fig. 10,) while its two lower arms 25 engage the transverse pivot-rod d'', that passes through a lug d''' of the feed-block.

Horizontally-reciprocating motion is im- 30 parted to the feed-block D by the cam C², Fig. 14, a fulcrumed lever d⁴, and links d⁵, which 35 connect the lower arm of the fulcrumed lever d⁴ with the pivot-rod d⁶ of the feed-block, as shown clearly in Figs. 2 and 3. The pivot-rod d⁶ is free to move in a slot at the ends of the lower arms of the lever d⁴, so as to follow the 40 horizontally-reciprocating motion imparted to the same by the lever d⁴ and links d⁵. The pivot-rod d⁶ is rigidly applied to the lug d''' of the feed-block D, so that the same is com- 45 pelled to follow the vertically and horizontally reciprocating motions imparted to the same by the motion-transmitting mechanism described. As the feed-block is pressed down on the tobacco it compresses the same and moves it forward into the contracted throat b. It is then raised and moved back ready to make the next forward stroke.

There is an adjustable connection between the pivot-links d⁵ and their actuating-lever d⁴, whereby the forward stroke of the feed-block can be regulated, and consequently the quantity of tobacco fed forward into the throat accurately determined. This adjustable connection may be effected by the bolt d¹⁰ passing through slots d⁹ in the links and 55 through a hole in the arm d⁴, said bolt being provided with a nut d¹¹ for clamping the links to the lever.

The front end or mouth of the contracted throat b communicates with a mold E, as 60 shown in Fig. 2. The mold E is shown in detail in Figs. 5, 6, and 7, and consists of a number of interior interchangeable mold-sections e, the concave faces of which correspond in size and shape to the bunch to be produced, 65 a mold-box E', a shell E², and a mold-carrier E³. The rear end of each mold-section e is provided with a stud e', to which is applied

a spiral spring e², the opposite end of which is seated against a shoulder of a set-screw e³, passing through the rear wall of the mold-box 70 E', which incloses the mold-sections e, as shown in Fig. 5. By adjusting the set-screws e³ from the outside the tension of the spiral springs e² is regulated, so that the required resistance to the tobacco fed to the mold-sections by the feed-block is obtained in imitation to the hand-pressure employed in making a filler by hand. As soon as the mold is filled with tobacco from the throat b, a vertically-reciprocating knife F descends and cuts 75 off the tobacco at the mouth of the throat, the cutting-knife remaining in lowered position, so as to close the front end of the throat b and prevent the escape of tobacco from the same and from the mold E. The vertically- 80 reciprocating motion of the cutting-knife F is produced by an oscillating lever f, that is pivoted at the front end to the supporting-frame A, and acted upon by a cam-groove of the cam C³. (Shown in Fig. 11.) The rear end 85 of the lever f is pivoted by an adjustable screw-rod f² with the shank of the knife, the rod f² being formed of two sections connected by a sleeve having a right and left hand screw-thread, so that the stroke of the cutting-knife can be accurately adjusted. The rod f² is pivoted to the shank of the knife, as 90 shown in Figs. 1, 2, and 4. The sides of the knife F are guided in fixed ways f⁴, so that the knife is steadily guided in its vertical up-and-down motion.

As soon as the mold E has received the required supply of tobacco by the descending motion of the cutting-knife F, which simultaneously closes the throat b, the mold E is 105 moved in downward direction along an arc-shaped guide-plate E^x, which connects the lower edge of the throat b with the rolling-table G. The arc-shaped guide-plate E^x is supported on arc-shaped arms e^x of the main 110 frame A, and serves to keep the mold E closed during its downward motion to the rolling-table. The mold E receives an oscillating motion along the guide-plate E^x by means of the cam C⁴, (shown in Fig. 8,) which engages 115 a vertically-reciprocating rack-bar e⁵, that is guided by its fork-shaped upper end along the shaft S. The rack-bar e⁵ meshes with a toothed segment e⁶, which is keyed to a crank-shaft e⁷, that is attached by arms e⁸ rigidly to 120 the mold-carrier E³, which incloses the mold-box E' and shell E², and serves to guide the latter by means of grooved ways on ribs of the former. The rack-bar e⁵, segment e⁶, and arms e⁸ impart an oscillating motion to the 125 mold until the same arrives in a position vertically above the pocket g of the rolling-table G, as shown in Fig. 7^a. When the mold is in this position, the box E' and shell E² are moved below the carrier E³, which motion is 130 produced by the cams C⁶ and C⁷, which are shown in Figs. 12 and 13, and the connecting-rods e⁹ and e¹⁰ and e¹¹ and e¹². When the shell E² is lowered, it forms contact with the edges

of the pocket g . Its motion is accomplished by the cam-groove of the cam C^6 , which groove engages the vertically-guided rod e^{11} , which is connected by a pivot-arm e^{12} to the shell E^2 , so that when the rod e^{11} and arm e^{12} are vertically in line with each other and with the pocket g the cam C^6 can lower the shell E^2 . In similar manner the mold-box E' of the mold E is actuated by a cam C^5 , rod e^9 engaged by the groove of the cam C^6 , Fig. 12, and a pivot-arm C^{10} applied to the mold-box E' , the latter being lowered into the pocket g simultaneously with the descending motion of the shell E^2 , as shown in Fig. 7^b. The greater stroke of the mold-box E' is produced by the greater eccentricity of the groove of the cam C^5 , the motions of the shell and mold-box serving to deposit the tobacco into the bight of the rolling-apron without giving it a chance to expand and change its shape. As soon as this is accomplished, the bunch-forming roller begins its motion and rolls the tobacco into the bight of the rolling-apron. Immediately before the motion of the bunch-forming roller commences the mold-box E' is first drawn back into the shell E^2 and then lifted with the same into line with the lower edge of the guide-plate E^x by the cams $C^6 C^5$, after which the mold is returned by the carrier E^2 , cam C^4 , rack-bar e , and toothed segment in upward direction along the guide-plate E^x to its normal position in line with the throat b .

The bunch-rolling device consists of a table G , a reciprocating roller G' , and a rolling-apron G^2 . The table G is constructed of a middle stationary portion g' and hinged and vertically-adjustable side portions g^2 g^3 , which latter are raised to varying angles of inclination to the middle portion by suitable set-screws g^3 , so that the shape of the rolling-table corresponds in its general outline to the shape of the bunch and the contour of the mold. The ends of the roller G' are applied to the slotted lower ends g^4 of a fork-shaped lever G^3 , which is fulcrumed to the supporting-frame A , while its upper end is engaged by a cam C^7 . (Shown in Fig. 9.) The roller G' is guided in slotted guide-frames g^5 at both sides of the rolling-table G , as shown in Figs. 1 and 2. At the end of the rolling-table G are arranged hinged and spring-actuated fingers g^6 , provided with projecting rests, to which the finished bunch is delivered from the bight of the rolling-apron. The side guide-frames g^5 are capable of vertical adjustment by means of slotted lugs g^7 , which are guided on upright lugs g^8 of a platform A^3 , supported on the bracket A' , so that the roller-guides can be adjusted higher or lower, according to the position of the hinged side portions of the rolling-table.

The rolling mechanism forms the subject-matter of a separate application, Serial No. 286,884, filed October 1, 1888.

The bunch is transferred from the rolling device to the mold, and finished by rolling a

wrapper around the same in the usual manner.

The successful operation of the machine depends on two conditions: first, upon the proper feed of tobacco, so that the required quantity of tobacco is cut off and supplied to the oscillating mold, and, secondly, upon the proper delivery of the tobacco from the mold to the bight of the rolling-apron formed in the pocket of the rolling-table. The feed is produced by the feed device described, while the proper delivery of the tobacco from the mold to the rolling-apron is accomplished by the oscillating motion of the mold and the vertically-reciprocating motions imparted to the mold-box and shell when they are in position vertically above the bight of the rolling-apron. In this position of the mold-box and guide-shell the tobacco in the mold is transferred in its original compact shape into the bight of the rolling-apron and then rolled into the binder by the forward motion of the bunch-forming roller, which motion commences immediately on the withdrawing of the mold-box and shell and serves to roll the binder around the filler, so as to produce the bunch in the usual manner.

The advantages of my improved cigar-bunching machine are that scraps of large size can be worked up without being first cut up into small pieces of uniform size in a scrap-cutting machine; secondly, that the required quantity of tobacco necessary for the bunch is fed into the mold and transmitted by the same in compressed shape to the bight of the rolling-apron and then rolled in the filler without changing its shape and position. This feature forms one of the main advantages of my improved machine, as thereby bunches of uniform shape and consistency are obtained which resemble closely bunches made by hand. The scrap-bunching machines heretofore in use are deficient in this respect, inasmuch as the proper shape and pressure on the tobacco forming the filler is not retained up to the moment when the filler is transferred and rolled in the binder by the action of the rolling-apron, so that bunches of irregular shape, in which the tobacco is unevenly distributed, are obtained, which is objectionable, inasmuch as good cigars require a uniform distribution of tobacco throughout the entire body thereof.

Having thus described my invention, I claim as new and desire to secure by Letters Patent—

1. The combination, with a feed mechanism having a horizontal supply-throat, of a reciprocating cutting-knife in front of said throat, a rolling mechanism below the feed mechanism, an arc-shaped guide-plate connecting the throat with the rolling mechanism, and a mold oscillating between the throat and rolling mechanism, substantially as set forth.

2. The combination of a supply-hopper having a laterally-extending throat, and a feed-roller in said throat, a vertically and horizontally reciprocating feed-block guided

in an opening of said throat, a reciprocating cutting-knife in front of the throat, a rolling mechanism below the level of the supply-throat, an arc-shaped guide-plate connecting the throat and rolling mechanism, and a rotary reciprocating mold oscillating along the guide-plate between the throat and rolling mechanism, substantially as set forth.

3. The combination of a feed mechanism 10 having a horizontal supply-throat, a vertically-reciprocating cutting-knife in front of said throat, a rolling mechanism below the level of the supply-throat, an arc-shaped guide-plate connecting the throat with the rolling mechanism, and a rotary reciprocating mold 15 composed of interior mold-sections, a mold-box, a guide-shell, and a mold-carrier, substantially as set forth.

4. The combination of a supply-hopper 20 having a laterally-extending throat, an intermittently-rotating feed-roller at the base of the hopper, and a vertically and horizontally reciprocating feed-block guided in an opening of the throat, said feed-block being provided 25 with a spring-plate extending below the top plate of the throat, substantially as set forth.

5. The combination of a feed mechanism having a horizontal supply-throat, a vertically-reciprocating cutting-knife guided in front of 30 said throat, a rolling mechanism below the feed mechanism, an arc-shaped guide-plate connecting the throat and rolling mechanism, a mold formed of an interior spring-actuated mold-section, a mold-box, a guide-shell, 35 and a mold-carrier, a cam-shaft, and mechanism, substantially as described, between the

cam-shaft and the mold-box, guide-shell, and mold-carrier, whereby an oscillating motion is imparted to the mold and a vertically-reciprocating motion to the mold-box and shell 40 when the mold arrives at the end of the guide-plate above the rolling mechanism, substantially as set forth.

6. The combination of a supply-throat, a rolling mechanism, an arc-shaped guide-plate 45 between the throat and rolling mechanism, a cam-shaft, a mold-carrier, mechanism between the cam-shaft and mold-carrier for oscillating the latter between the throat and rolling mechanism, a guide-shell in the mold-carrier, a mold-box in the guide-shell, and mechanisms between the cam-shaft and the guide-shell, and mold-box for reciprocating both when the mold-carrier arrives at the lower end of the guide-plate vertically above 55 the pocket of the rolling mechanism, substantially as set forth.

7. In a cigar-bunching machine, a mold composed of interior spring-pressed mold-sections, a mold-box inclosing said sections, a 60 ribbed guide-shell inclosing the mold-box, and an exterior mold-carrier provided with guideways for the guide-shell, substantially as set forth.

In testimony that I claim the foregoing as 65 my invention I have signed my name in presence of two subscribing witnesses.

FERDINAND J. HAGEN.
